UNITED STATES PATENT OFFICE.

EDWIN T. BASKIN, OF INDEPENDENCE, MISSOURI.

BRUSH.

SPECIFICATION forming part of Letters Patent No. 722,666, dated March 17, 1903.

Application filed April 7, 1902. Serial No. 101,640. (No model.)

To all whom it may concern:

Be it known that I, EDWIN T. BASKIN, a citizen of the United States, residing at Independence, in the county of Jackson and State of Missouri, have invented new and useful Improvements in Brushes, of which the following is a specification.

My invention relates to brooms and to long-handled brushes.

10 My invention consists, first, in passing the bunches of stock or material transversely through the block instead of up and down in the usual manner; second, in making a brush in two or more sections for heavy work, 15 each section having a separate block; third, in a novel clamp for holding together the blocks of the brush, so that a brush of any required thickness may be made.

The advantage of passing the brush-stock 20 through the block transversely will be understood from the specification and stated hereinafter.

The object of having a plurality of blocks in one brush is to provide a thick brush in 25 which the stock will be solid and practically homogeneous, and this plurality of blocks is a necessary result of the novel manner in which I pass the stock through the blocks.

Referring to the accompanying drawings, 30 Figure 1 is a perspective view of a brush or broom embodying my invention, the handle being broken off. Fig. 2 is a side elevation, partly in section, of the handle-casting detached. Fig. 3 is an elevation of the inner 35 side of one of the sections or halves of the brush. Fig. 4 is a transverse section of a brush and its clamp, taken on a line corresponding to line IV IV of Fig. 3. Fig. 5 is a transverse section of a complete brush, taken 40 on a line corresponding to line V V of Fig. 3. Fig. 6 is a section through a portion of one of the blocks, taken on line VI of Fig. 3. Fig. 7 represents a handle-casting designed especially for brooms, while the handle-casting 45 shown in Fig. 2 is adapted for white-wash-brushes, roofing-brushes, &c. Fig. 8 is a top plan view of the middle portions of the blocks, the ends being broken away.

In the brush illustrated in the drawings 50 two blocks 4 and 4 are employed. These blocks are separable from each other, but

when in use are held together by a clamp composed of a handle-casting 5 6 and a pair of T-bolts 2 3. The handle-casting comprises a socket portion 5 and two oppositely-extending T-shaped arms 6 and 6. At the respective ends of each arm 6 are two clamping-bosses 7, which fit in recesses 8 in the tops of the blocks 4. Through a hole in each arm 6 passes a T-bolt 2 3. These bolts extend between the blocks 4 in grooves 9, cut for the purpose, and on the inner face of each end of each cross-piece 3 is a clamping-boss 10. These bosses 10 enter sockets 12, provided therefor in the blocks 4. All of the 65 bosses 7 and 10 are drawn into their sockets by nuts 13 on the bolts 2 3. Thus when the nuts are tight the blocks 4 are held together by the combined action of the arms 6 and the bolts 2 3. For brushes the socket 5' of 70 the handle-casting will be oblique, as shown in Fig. 2. For brooms it will be perpendicular to the arms 6, as shown in Fig. 7.

Figs. 3 and 6 illustrate the direction in which the bunches of stock pass through 75 each block. It will be seen that the stock passes transversely through the block and preferably in an oblique direction, as shown in Fig. 6. By passing each bunch of stock only once through a hole, as shown, any 80 sharp bending of the bristles is obviated and the binding-wires 14 are placed at a distance from the bends 15, so that the stock is not liable to be cut thereby. The oblique direction of the holes through the blocks is better 85 adapted for certain kinds of brushes than for others.

Any required number of sections may be assembled to form one brush or broom, and handle-castings with arms of different lengths 90 provided with bolts having cross-pieces of different lengths may be employed to clamp the sections together.

In the adjacent faces of the two middle blocks 4 or in each block when there are but 95 two I cut a recess 16. The two recesses 16 when placed together form a continuation of the socket in the handle-casting 5 6, so that the handle may be extended through said casting into the socket formed by said recesses and will be braced thereby, so that 100 when the broom is doing heavy duty a part

of the strain will be taken from the socket portion of the handle-casting and borne by the arms 6 and bosses 7.

Having now fully described my invention, 5 what I claim as new, and desire to secure by Letters Patent of the United States, is—

In a brush or broom, a plurality of blocks, each block having transverse holes therein, bristles passed once through each of said 10 holes, each block having recesses 8 and 12 therein, and a clamp comprising a handle-casting provided with T-shaped arms and a

pair of T-bolts passing through said arms respectively, said bolts having projections thereon entering said recesses 12, and said 15 arms having projections thereon entering said recesses 8; substantially as described.

In testimony whereof I affix my signature in the presence of two witnesses.

EDWIN T. BASKIN.
